G. E. MARLATT

TYPOGRAPHICAL SLUG CASTING MACHINE

Filed Nov. 13, 1926

UNITED STATES PATENT OFFICE.

GEORGE E. MARLATT, OF PASADENA, CALIFORNIA.

TYPOGRAPHICAL SLUG-CASTING MACHINE.

Application filed November 13, 1926. Serial No. 148,304.

My invention relates to means for insuring a reliable delivery from their mold of type-slugs as cast by machines of the linotype class. In such machines the mold is mounted in a rotatable carrier which positions the mold in an upper horizontal position to receive the cast of metal and thereafter carries the mold to a vertical position where it is held stationary and the slug ejected therefrom between trimming knives and thence into a receiving and assembling tray usually called a galley. This galley is positioned either vertically or angularly according to whether the machine on which it is mounted is intended to be used only for producing short "news" slugs or for producing slugs of miscellaneous lengths and thicknesses. When the galley is mounted angularly the slugs therein are visible to an operator for purposes of inspection, but their delivery to and into the galley is unreliable and annoying. My present invention is directed to improving the delivery of the slugs into a galley thus angularly mounted, and also to providing for the employment of two galleys on the same machine for selective use according to the length, quantity or character of slugs being produced and the preference of an operator. The structure and mechanism involved in attaining this objective is illustrated in the accompanying drawings, in which—

Fig. 1 is a front elevation of the slug-casting portion of a linotype machine, showing both a vertical and an angular galley in their position relative to the mold and trimming knives and the slug-delivery channel leading therefrom. In this view the slug-delivery channel is in position to deliver slugs to the angular galley.

Fig. 2 is a replica of a portion of Fig. 1 except that the slug-delivery channel is shown adjusted to permit the delivery of slugs into the vertically-mounted galley.

Fig. 3 is a left-hand view of Fig. 1.

Fig. 4 is a view of the slug-delivery channel on the line 4-4 of Fig. 1.

Heretofore the galleys of either form have been held stationary and the slugs pushed into them by the end of a lever mounted similarly to the galley-supporting lever A of this invention. The result has been that the slugs would frequently strike this pusher before or instead of entering the galley. Hence I eliminate this pusher and render

the galleys movable longitudinally in lieu thereof. Referring first to the slug-delivery channel B: The channel proper B¹ thereof serves only for delivering slugs to the angular, or lower, galley C, and for such purpose is moved to the left on a pivot-shaft D, thus placing the channel B¹ in front of the mold slot E from which the slugs are ejected. It is held in this left-hand position when a right-hand slot B³ is made to engage a stud F¹ in the machine frame F. When the left-hand slot B⁴ is engaged with the stud F¹ the channel B as a whole is moved from in front of the mold slot to permit the slugs to enter on the vertically-mounted, or upper, galley G. The slots B³, B⁴ are through an extension B⁵ from the inner side wall B⁶ of the channel B¹, and the channel is pivotally movable on its shaft D for the purpose of engaging and disengaging the slots from the stud F¹. The channel B¹ is provided with a floor B⁷ which terminates flush with the floor of the lower galley C and on this floor the slugs are supported as they slide from between the trimming knives (not shown) through the channel and into the lower galley. The outer wall B² of the channel extends beyond the inner wall and the floor thereof and across the floor of the galley, and provides an abutment against which the slugs S are stopped when the galley moves longitudinally to the right as indicated in dotted lines in Fig. 1. When the galley thus moves to the right the slugs therein will be packed against the wall B², and when it moves to the left the slugs will be carried therewith, thus leaving a space between the last, or end, slug and the wall B², and into this space the slug next ejected will enter. The movement of the galley is repeated each time a slug enters therein, and for the purpose of such movement is indirectly mounted at its right-hand end on the upper arm H¹ of a crank-like lever H the pivot end H² of which has a bearing in the frame F; and at its left-hand end it is indirectly supported on the lower arm I¹ of a swinging lever I having a pivoted bearing in a bracket J secured to the frame F. The galley C is removably and directly supported on a bracket K pivotally supported at its opposite ends on the swinging horizontal arms H¹ and I¹ of the levers H and I respectively. The galley moves to the right by gravity by reason of the angularity of the levers H and I.

relative to the perpendicular, and is returned to the left by means of a cam L rotatable incidental to the normal rotation of a mold-carrier driving-pinion M with which it is integral. For the purpose of imparting movement to the galley C, connection between the cam L and the swinging lever I is established by means of an arm O rigidly secured to the lever I. Since the pinion M rotates four times incidental to a rotation of the mold carrier N each time a slug is cast, and since two reciprocations of the galley C are considered sufficient to move the slugs therein as explained, I provide clearances P¹ and P² on the usual first elevator P, and extend the arm O to engaging relation with the elevator P. Thus, when the elevator P is in its down position the clearance P¹ will permit a movement of the galley C preliminary to the deposit of a slug therein, and when the elevator P is in its highest position the second clearance P² will permit a second movement of the galley following the entry of a slug therein. Between the clearances P¹ and P² an anti-friction roller O¹ on the arm O engages the full surface P³ of the edge of the elevator P and thus holds the galley stationary during two rotations of the pinion M.

The upper galley G has a reciprocating movement similar to that described for the lower galley and under control of the same mechanism, both galleys moving together whether in use or idle. When the upper galley is idle as a slug-receiver it is adjusted to the left in order to permit the channel B to be positioned to the left in front of the mold for conducting slugs to the lower galley. For the purpose of such adjustment the upper galley is provided with two studs G³, G² either of which may be made to engage a notch O² in an angle O³ of an extension O⁴ from the arm O. At its left end the galley G is supported on the arm extension O⁴ and at its right end is suspended on a swinging link Q, hence by seating the left-hand stud G³ in the notch O² the galley is rendered operative, and by seating the right-hand stud G² in the notch the galley is adjusted to inoperative position. But in either position the galley G has a reciprocating movement with the arm O, and this movement of the galley when inoperative as a slug-receiver is utilized to cause an abrupt and precipitous drop of the slugs into the channel B¹ in order that they may acquire sufficient momentum to carry them dependably to the lower galley. With this object in view the floor G¹ of the upper galley is made to clear through a notch B⁸ in the inner wall B⁶ of the channel B and to extend across the path of the slugs regardless of the adjustment of the galley G; hence when slugs destined for the lower galley emerge from the mold and trimming knives, they are mo-

mentarily supported on the end of the floor G¹, and as the upper galley reciprocates to the left the slugs are scraped from the floor G¹ against the inner channel wall B⁶ and drop abruptly through the channel to the lower galley. When the upper galley G and channel B are adjusted to the left as in Fig. 1, the reciprocating movement of the upper galley to the right will place the floor G¹ thereof in about the position shown in Fig. 2, relative to the mold, and when retracted to the left the floor will move from in front of the mold and out of the channel B¹, permitting the slug to drop. In Fig. 2 the elevator P is in raised position with the anti-friction roller O¹ occupying the depression P², therefore the galleys are moved to the right; and since the channel element B is also to the right in Fig. 2, therefore when the galleys are retracted to the position shown in Fig. 1 as the elevator descends, the floor G¹ of the upper galley will move from the channel B¹ and the slug which has been deposited thereon will drop to the lower galley.

When the upper galley G is operative to receive slugs, the channel B is adjusted to the right as in Fig. 2 and the slugs are ejected directly to a position on the floor G¹ of the galley. As controlled by the clearance P², the galley G then moves to the right and the slugs therein are packed against the outside of the inner channel wall B⁶; and when the galley moves to the left the slugs therein are carried therewith, leaving space between the end slug and the wall B⁶ for the entry of a succeeding slug.

Having thus described my invention and the advantages of its use, what I claim as new and desire to secure by Letters Patent, is:

1. In a slug casting machine, a slug receiver having a reciprocating movement for the purpose of advancing the slugs thereon step by step as they enter therein.

2. In a slug casting machine, a reciprocating slug receiver and a relatively stationary abutment across the receiving thereof, whereby successive movements of said receiver in one direction will pack the slugs therein against said abutment and successive movements thereof in the opposite direction will move the slugs therein away from said abutment and thus provide space for the successive entry of slugs into said receiver.

3. In a slug casting machine, in combination with a mold in which slugs are cast, a slug receiver mounted angularly below said mold, and a channel through which slugs are conducted from said mold to said receiver, means for causing the slugs to drop precipitously into and through said channel, said means being a slug-support automatically movable to and retractable from a position across said channel in front of said mold,

whereby slugs are momentarily retarded on said support and drop into said channel when said support is retracted.

4. In a slug casting machine, in combination, a mold from which slugs are ejected, a slug receiver mounted vertically in a plane in front of said mold and a slug receiver mounted angularly in a plane below said mold, a channel for conducting slugs from said mold to said angularly-mounted receiver, and means whereby either of said

slug receivers may be used, selectively, said means consisting in rendering said channel adjustable to a non-interfering position when said vertically mounted receiver is in use, and in rendering said vertically-mounted receiver adjustable to a non-interfering position when said channel and said angularly-mounted receiver are in use. 15

Signed at Pasadena, Los Angeles County, 20 California, this 19th day of October, 1926.

GEORGE E. MARLATT.
